Patented Aug. 26, 1924.

UNITED STATES PATENT OFFICE.

ALESSANDRO LALLI, OF BERWYN, PENNSYLVANIA.

ATTACHMENT FOR SHOE-SOLE-STITCHING MACHINES.

Application filed February 19, 1923. Serial No. 619,856.

To all whom it may concern:

Be it known that I, ALESSANDRO LALLI, a subject of the King of Italy, residing at Berwyn, in the county of Chester and State 5 of Pennsylvania, have invented certain new and useful Improvements in Attachments for Shoe-Sole-Stitching Machines, of which the following is a specification.

This invention relates generally to shoe machinery, having more particular reference to an attachment for machines for stitching the soles of shoes, the invention being designed more particularly for use in connection with the machine known commercially as the Victor lockstitch machine.

In machines for stitching the soles of shoes it is customary to provide a guard plate in front of the awl, both to protect the hand of the mechanic and also to prevent the awl from accidentally piercing the upper of the shoe. In the Victor machine above referred to a plate of this sort is provided, but it is disadvantageous in that it does not adequately protect the hand that is holding the shoe against the work table, the present invention having for an object to provide a form of guard plate which can be readily applied to machines already in use in place of the present guard plate, and which also is arranged for adjustment to permit of the marginal portion of the sole being positioned to have the line of stitching at such slightly different distance from its extreme edge as may be desired.

For further comprehension of the invention, and of the objects and advantages thereof, reference will be had to the following description and accompanying drawings, and to the appended claims in which the various novel features of the invention are more particularly set forth.

Fig. 1 of the drawings is a face view of my improved guard plate indicating it in position on a sole stitching machine.

Fig. 2 is a transverse vertical sectional view taken along the line 2—2 of Fig. 1.

Fig. 3 is a top view of the guard plate alone.

Fig. 4 is a detail transverse section along the line 4—4 of Fig. 1.

Fig. 5 is a detail elevation of the locking element for the U-strap which engages one of the frame arms of the machine to adjustably position the guard plate.

Fig. 6 is a detail perspective view of this U-strap.

The fragmentary showing of the machine parts in Fig. 1 of the drawings show the machine as seen in face view, as well as showing the guard plate in face view. In these machines the main frame presents a vertical wall element 10 which extends in a direction from front to rear thereof and is positioned to the left of the stitching elements. From this wall element 10 a fixed 65 arm 11 projects to the right and forms a support or table upon which the edge of the sole to be stitched, indicated at S in Fig. 2, is placed as indicated in said figure, the awl working upward through a suitable 70 aperture in the end of this arm, and the needle working downward. The awl and the needle are indicated simply in Fig. 2 by the arrows 12 and 13 respectively.

With the usual type of guard plate provided in this machine the space to the left of the needle and awl is left unguarded, and there is a danger of the workman getting one of his fingers in the way of either awl or needle. To obviate this, and also to provide for adjustment of the guard plate as previously specified, the latter is secured upon the face of the wall element 10 and is twisted or bent to extend to the right along the front edge of the arm 11 below the latter. The guard plate as a whole is numbered 15, the lower portion which is secured to the wall element 10 is numbered 15', and the upper portion which is extended along the arm 11 is numbered 15".

In order to secure the guard plate 15 to the wall element 10 it is not needful to bore any additional holes therein or to make any changes in the structure thereof, the guard plate being attached to the wall by loosening the screw 17 upon which one of the thread feed pulleys 18 is mounted and placing the guard plate on the screw between the said pulley and the face of the wall 10, the guard plate having a suitable hole 19 in the lower end thereof to receive the screw 17. As the guard plate is of thin metal it may be so attached to the wall without in any way interfering with the functioning of the pulley.

On account of the thinness, and consequent resiliency, of the guard plate an additional holding means for the portion 15" thereof is required, the novel means I have here shown comprising a U-strap 22 which straddles the arm and is secured at its ends to the guard plate. To permit of desired varia-

tion of the positioning of the guard plate this U-strap is secured to the latter as follows: Formed in the guard plate is a hollow boss 25 which is internally screw 5 threaded and into which there is threaded a sleeve 26 of greater length than the said boss and whose ends are preferably slightly rounded as shown.

The ends of the strap straddle the ends 10 of this sleeve and are formed with suitable openings 27 through which is passed a bolt 28 having a nut 29 threaded thereon, the bolt passing through the sleeve and being of smaller diameter than the bore of the latter 15 to permit of angular adjustment. The sleeve is formed with a longitudinal slot 30 in one wall thereof which enters from the end adapted to have the head 28' of the bolt adjacent it, this slot 30 terminating near the 20 other end of the sleeve. Formed on the head of the bolt 28 is a wedge shaped projection 31 which is adapted to engage in the open end of the slot 30 to expand the sleeve 26 when the nut 29 is tightened, and 25 thus bind the sleeve in the boss 25, as well as bind the strap 22 on the sleeve. By this means such adjustment as may be required can be readily obtained, as the sleeve can be moved longitudinally in the boss 25, while 30 the angle of the strap 22 can be varied because of the bore of the sleeve being larger than the screw 28. To accommodate the wedge 31 the aperture 27 in one end of the strap 22 is extended at the top as shown 35 at 27'.

In the use of these machines it is customary for the workman, after properly positioning the shoe with the edge of the sole in proper relation to the awl and needle, to 40 move the shoe along the support with the right hand, while gripping the shoe with the left hand to ensure of the upper being drawn taut, and with my improved guard plate all 45 danger of hurt to the left hand from either needle or awl is prevented.

Having thus described my invention what I claim as new and desire to protect by Letters Patent of the United States is as follows:

50 1. In a shoe sole stitching machine, an awl and a needle, a wall element extending from front toward the rear of the machine, an arm projecting from said wall element into the path of said awl and needle, and 55 a guard plate secured both to said wall element and to said arm, the means for securing the said guard plate to said arm comprising a U-strap straddling the arm and secured at its ends to the said guard plate.

60 2. In a shoe sole stitching machine, an awl

and a needle, a wall element extending from front toward the rear of the machine, an arm projecting from said wall element into the path of said awl and needle, and a guard plate secured both to said wall element and 65 to said arm, the means for securing the said guard plate to said arm comprising a U-strap straddling the arm and secured at its ends to the said guard plate, said guard plate comprising a lower portion lying in 70 contact with said wall element and an upper portion extending along said arm.

3. In a shoe sole stitching machine, an awl and a needle, a wall element extending from front toward the rear of the machine, an arm 75 projecting from said wall element into the path of said awl and needle, and a guard plate secured both to said wall element and to said arm, the means for securing the said guard plate to said arm comprising a U- 80 strap straddling the arm and secured at its ends to the said guard plate, said guard plate comprising a lower portion lying in contact with said wall element and an upper portion extending along said arm, said U-strap 85 being secured to said upper portion.

4. In a shoe sole stitching machine, an awl and a needle, a vertical wall element extending in a direction from front to rear of the machine, a fixed arm projecting from said 90 wall element onto the path of said awl and said needle, a U-strap straddling said arm, a sleeve threaded through an aperture in said plate and straddled at its ends by the ends of the said strap, a bolt passed through 95 the sleeve to secure the ends of the said U-strap to the latter, and a device adapted to secure the said sleeve against movement in the said aperture by tightening the said bolt.

5. In a shoe sole stitching machine, an awl and a needle, a vertical wall element extending in a direction from front to rear of the machine, a fixed arm projecting from said 100 wall element onto the path of said awl and said needle, a U-strap straddling said arm, a sleeve threaded through an aperture in said plate and straddled at its ends by the 105 ends of the said strap, a bolt passed through the sleeve to secure the ends of the said U-strap to the latter, and a device adapted to secure the said sleeve against movement in the said aperture by tightening the said bolt, said means comprising a wedge shaped 110 projection on the head of the bolt adapted to engage in a longitudinal slot in the sleeve 115 to expand the latter.

In testimony whereof I have affixed my signature:

ALESSANDRO LALLI,
